UNITED STATES PATENT OFFICE.

RUDOLPH W. AUER, OF PHILADELPHIA, PENNSYLVANIA.

ORNAMENTAL FIREPLACE GRATE.

Application filed December 17, 1925. Serial No. 76,113.

This invention relates to ornamental fireplace grates of the type in which burning is simulated by projection of electrically produced light and heat through imitation coals 5 of colored translucent material.

Amongst the objects of my invention are to attain, in ornamental devices of the above kind, a closer and better simulation of actual coal burning than possible with means here- 10 tofore generally employed for this purpose; to secure the advantages of simplified construction, especially with regard to facilitating economic manufacture; and to provide for ready access to parts likely to require replace- 15 ment from time to time.

With reference to the drawings, Fig. I is a plan view of an ornamental fireplace grate conveniently embodying my invention, certain portions being broken away and shown 20 in section to disclose important underlying details.

Fig. II is a front view of the grate.

Fig. III is a longitudinal section taken as indicated by the arrows III—III in Fig. I; 25 and,

Fig. IV is a transverse section taken as indicated by the arrows IV—IV in Fig. I.

In carrying out my invention I employ an open-topped housing 10, the frame whereof 30 comprises a solid back wall member 11 with legs 12, 12, a somewhat longer front member 13 that is grated vertically between ornamental end leg posts 14, 14 as best shown in Fig. II, and solid end wall members 15, 16 extending transversely between said back and the front members. These frame parts are preferably made as castings and secured together 35 at various points by screw bolts 17, Fig. 1. An internal perimetric ledge 18 afforded 40 jointly by the several frame members 11, 13, 15, 16 serves as the support for a separable insert bottom member 19, which is in turn secured by screws 20 taking into said ledge. Extending horizontally across the housing 45 10 near the top, and down behind the grated front 13, is an angularly bent foraminous partition 21, preferably of coarse wire mesh, with its opposite ends curled about tie rods 22, 23 extending longitudinally between the end 50 wall members 15, 16 of the housing frame 10. This partition 21 provides a horizontal support and a frontal interspace for imitation coals such as conventionally represented at C, and at the same time sets apart an inner chamber 24.

Centrally within the inner chamber 24 I

place a conventional form of electric heating device 26, and at opposite sides somewhat to the rear of said device, electric bulbs 27, 27. Wire brackets 28, 28 serve to support angularly-vaned pin wheels 29 centrally over the bulbs 27, 27 for rotation by currents set up as a result of localized heating of air. When access is required to the chamber 24 for bulb replacement, adjustments, etc., this may be 60 had through an opening 30 in the back wall member 11, said opening being normally closed by a door 31 retractable about a pivot stud 32.

The bottom member 19 of the housing 10 is 70 hollow and made of sheet metal with a cover plate 33 that is polished and longitudinally corrugated for a purpose hereinafter explained, and embodies a recessed lower section 34 which extends down beneath the level 75 of the perimetric supporting ledge 18 as shown in Figs. III and IV. The hollow section 34 of the bottom member 19 is utilized to accommodate and conceal the wiring to the 80 sockets 35, 36 respectively for the heating device 26 and the illuminating bulbs 27, 27, said sockets being interposed in parallel circuits connected to a common duplex cable 37 which extends through an insulating bushing 38 at the rear of the grate where it is equipped 85 exteriorly with a plug 39 capable of being screwed into a wall or base socket such as usually provided for connection of electric appliances. The heating device 26 and the lighting bulbs 27, 27 are separately control- 90 lable by snap switches 40, 41 allocated for convenience of access, at opposite ends of the hollow bottom member 19.

In accordance with my invention, the coals C may be of broken glass slag having a reddish brown tint, with some clear so as to be translucent throughout, some with roughened or frosted surfaces (as indicated by speckled shading in Fig. II) which render them partially opaque, and others embodying both 95 these characteristics. By proper choice and arrangement, these different varieties of coals may be advantageously placed to represent a combination of live coals and faintly incandescent fuel, with the latter in excess at the lower portion of the grate front 13. By employing coals of reddish brown as specified, and using electric bulbs with an orange tint, the resultant color effect of the light seen 100 through the coals will be that of an intensely burning fire. The fluctuation caused by rotation of the pin wheels 29 is heightened and 105 110

made more realistic through reflection of the light by the corrugations of the plate 33. The heat emanating from the device 26 is absorbed by the coals C, and by them radiated 5 and diffused outwardly in a very effective manner.

In manufacturing the grate, the bottom member 19 is separately assembled with the heating device 26, bulbs 27, 27, and all the 10 wiring connections, etc., so that the same may be handled as a unit in placing it within the housing frame 10. Such simplified construction, it will be seen, has the advantage of materially reducing manufacturing costs. By 15 provision of the door 31 in the back of the housing 10, all the parts at the interior may be reached without entailing dismantling of any of the surrounding parts of the organization. From the foregoing it will be further apparent 20 that my improved grate lends itself advantageously to ready packing for shipment, and may be easily installed without entailing special electrical connections for its operation.

25 Having thus described my invention, I claim:

1. An ornamental electric fireplace comprising an open-topped housing with a grated front, a solid back and side walls, a separable 30 corrugated bottom reflector plate having a recessed lower section; a foraminous partition extending across the top of the housing and down behind its grated front with provision of a horizontal supporting and a vertical 35 frontal interspace, for translucent imitation coals, as well as an inner chamber; vertically-directed electric illuminating and heating means within said chamber to project light and heat through the translucent coals; 40 pin wheels supported by angled brackets directly over the illuminating means to produce flickering; and a door protecting an opening in the back walls of the housing

through which access is had to parts at the interior.

2. An ornamental electric fireplace comprising an open-topped housing with, a grated front, a solid back and side walls all affording an internal perimetric ledge for support of a separable hollow bottom; a 50 foraminous partition extending across the top of the housing and down behind the grated front with provision of a horizontal support and a vertical frontal interspace, for translucent imitation coals, as well as an inner chamber; vertically-directed electric illuminating and heating means within said chamber; and independent control switches 55 therefor all mounted on the separable bottom with the wiring connections concealed in the 60 hollow thereof.

3. An ornamental electric fireplace comprising an open-topped housing with, a grated front, a solid back and side walls, a separable longitudinally corrugated insert bottom supported on an internal peripheral ledge of the housing frame and having a recessed lower section; a foraminous partition extending across the top of the housing and down behind its grated front with provision of an inner chamber, a horizontal support, and a vertical 70 frontal interspace; imitation coals overlying and in front of said partition, some of which is entirely translucent, some semi-opaque, and others partly translucent and partly 75 opaque; vertically-directed electric illuminating and heating means within the aforesaid chamber; and independent switches therefor all mounted on the separable corrugate bottom with the wiring connections concealed in the recessed lower section thereof.

In testimony whereof, I have hereunto signed my name at Philadelphia, Pennsylvania, this 11th day of December, 1925.

RUDOLPH W. AUER.
